Pequignot + Myers LLC(57) **CLAIM**

The ornamental design for a thermal pack, as substantially shown and described.

DESCRIPTION

FIG. 1 is a perspective view of a thermal pack showing the new design.

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The bead fill-volume depicted in the drawings of the thermal pack is shown for example purposes only and is not intended to limit the scope of the invention with respect to any specific bead fill-volume amount. Structure illustrated in broken lines is provided to illustrate the environment of the invention but is not otherwise part of the claimed design.
